UNITED STATES PATENT OFFICE.

WATSON R. SMITH AND GUSTAV A. FRANZ, OF JACKSON, MICHIGAN, ASSIGNEES TO
JACKSON CUSHION SPRING COMPANY, OF JACKSON, MICHIGAN.

SPRING STRUCTURE.

1,150,789.

Specification of Letters Patent. Patented Aug. 17, 1915.

Application filed August 5, 1912. Serial No. 713,873.

To all whom it may concern:

Be it known that we, WATSON R. SMITH and GUSTAV A. FRANZ, both citizens of the United States, and both residing at Jackson, in the county of Jackson and State of Michigan, have invented certain new and useful Improvements in Spring Structures, of which the following is a specification.

This invention relates to spring structures. 10 The main object is to provide a spring structure for chairs, cars, beds, automobile or other vehicles embodying among other characteristics means whereby when the structure is upholstered there will be formed 15 at the upper front edge thereof a roll with a minimum amount of hair and upholstering material and which will produce not only an attractive front but provide for a soft, pliable upper front edge in contradistinction to 20 the usual stiff edge and square facing effect.

Another object resides in the provision of a spring structure embodying an arrangement and organization of parts to obviate all the strain incident to the weight of the 25 rider being placed on the border wires and to provide for considerable flexibility without danger of the main springs of the structure becoming disconnected with relation to one another.

With the above and other objects in view the present invention consists in the combination and arrangement of parts herein-after described, illustrated in the accompanying drawings and particularly pointed 35 out in the appended claims, it being understood that changes may be made in the form, proportion, size and minor details without departing from the spirit or sacrificing any of the advantages of the invention.

In the drawings: Figure 1 is a top plan view of the invention. Fig. 2 is a front elevation. Fig. 3 is a vertical sectional view.

Referring now more particularly to the 45 accompanying drawings the reference character 10 indicates a lower frame to which may be connected by means of suitable clips 11 supporting wires 12 upon which may be mounted the main springs A, the 50 front row of springs being arranged preferably in upper and lower sets 13 and 14 with the springs 13 and 14 connected together preferably by means of suitable clips 15, said clips engaging opposite sides of the 55 upper convolutions of the lower springs 14

and the upper springs 13 being preferably secured to the clips 15 by means of suitable rivets 16.

The character B indicates an upper frame which is disposed preferably upon a slight 60 rearward incline with respect to the lower frame so that in the event of the vehicle striking an obstruction in the roadway or otherwise jolting the rider there will be a 65 tendency of the rider to be thrown backwardly rather than forwardly off of the seat. This top frame B is not continuous but preferably has an open front. Its side portions at the front of the upper corner springs 13 are directed inwardly as at 18 70 and secured at these points by means of suitable clips 19 to the upper front corner springs of the structure. From these upper front corner springs the front portions of the top frame are directed downwardly upon 75 an incline as at 20, terminating short of each other, and secured to a wire 21 by means of suitable clips 22. It is preferable to form upwardly directed kinks 23 in the wire 21 where the aforesaid clips 22 connect the inclined portions 20 of the upper frame with said wire 21 and to slightly deflect inwardly the extremities of the inclined portions 20, as at 25, so that the clips 22 cannot slide on the wire 21 by virtue of 80 which, and the extremities of the portions 20 of the upper frame being deflected, as at 24, the side portions of the top frame, and consequently all of the side springs cannot 85 be deflected sidewise either inwardly or outwardly of the structure, thereby insuring vertical movement of the side springs of the structure. Furthermore, by virtue of these inclined portions 20 of the top frame, the upper front corner springs of the structure 90 are rendered less resilient than the springs at the upper front portion intermediate these corner springs. The rider usually 95 seats himself centrally of the structure and, by virtue of the upper frame A being not continued across the structure but arranged as described, the upper frame is open at its front, and the front row of springs, between the front corner springs are very pliable so that the upper front edge of the 100 structure possesses such resiliency as to give comfort to the rider under normal or abnormal conditions.

The wire 21 has rearwardly directed horizontal portions 25 which are secured to the 105 110

outer sides of the lower corner springs 14 by means of suitable clips 26 and from these lower front corner springs these horizontal portions 25 of the wire 21 are directed downwardly upon an incline as at 27 with their extremities connected to the lower frame 10 by means of suitable clips 28, one clip 28 being on the side of the base frame and one clip 28 being disposed preferably at the rear 10 of the base frame. However, the extremities of the inclined portions 27 of the wire 21 may be secured to the base frame in any suitable manner and it will be understood that the wire 21 being arranged as shown 15 and described tends to stiffen the front of the structure to prevent a complete compression of the same at its front. Notwithstanding this stiffening of the front of the structure, however, the peculiar formation 20 of the upper frame with the front row of springs intermediate the front corner springs unconnected with the upper frame, there is considerable elasticity at the upper front edge of the structure. If desired, the 25 wire 21¹ may be connected at one end to the lower frame 10 and arranged upon an upward incline with its other end connected to the wire 21 by means of a suitable clip 21^a to coöperate with the aforesaid side portions 30 27 of the wire 21.

To provide the upper front edge of the structure with means whereby a pliable roll edge may be formed at the upper front portion thereof, we may employ steel bands C 35 each of which bands is preferably bent intermediate its ends to provide a substantially U-shaped member including a bight portion 29 and upper and lower leg portions 30 and 31, respectively. There is preferably 40 arranged one band for each row of springs 13 which extend from the front to the rear of the structure. The lower leg portion 31 of each yieldable element C is preferably secured to the aforesaid clips 15 by means of 45 the same rivet 16 that secures the upper front springs 13 to said clips 15. The upper leg portions 30 are preferably secured to the upper convolutions of the springs of the structure by means of suitable rivets 33. 50 The bight portion 29 of these bands overhangs or projects beyond the upper front portion of the structure and provides for the formation of a soft pliable roll at the front edge of the cushion. These yieldable 55 elements C have comparatively short leg portions, both of which leg portions of each yieldable element terminate short of the second row of springs from the front of the structure and preferably short of the inner 60 sides of the convolutions of the front row of springs, and to insure against any possibility of a sliding movement of the aforesaid clips 15 it will be noted that the wire 21 is preferably provided with downwardly 65 directed kinks 34 in which the outer ends

of the clips 15 engage in fastening said clips to the front row of springs. If desired, the lowermost springs 14 may be connected at their tops by means of suitable links 35 to prevent any sidewise movement thereof, and similar links 36 may be used for connecting the upper convolutions of the remaining springs to prevent sidewise movement, if desired. 70

The upper convolutions of the rows of 75 springs extending from the front to the rear of the structure are preferably connected together by means of short coil springs 37 which expand and permit flexibility and yet prevent liability of the 80 springs tearing apart from the front to the rear of the structure, and by virtue of which coil springs and the coiled main springs there is in reality a flexible connection between the upper leg portions of the yieldable elements C and the rear of the upper frame. 85

What is claimed is:—

1. A spring structure comprising upper and lower frames, springs arranged between the frames, a wire extending across the front of the structure between the upper and lower frames and connected to the front row of springs, said wire having its ends directed rearward in substantially horizontal planes around the front corner springs and connected to the sides of the latter, said substantially horizontally disposed end portions of said wire element terminating in downwardly inclined portions which are 100 connected to the lower frame so as to prevent buckling of the front row of springs, the upper frame being open at its front and including inclined portions which are unconnected with the front row of springs, and means for connecting the inclined portions of the upper frame to said wire element so as to prevent inward or outward tilting of the front corner springs. 105

2. A spring structure comprising upper and lower frames, springs arranged between the frames, a wire extending across the front of the structure between the upper and lower frames and connected to the front row of springs, said wire having its ends directed rearward in substantially horizontal planes around the front corner springs and connected to the sides of the latter, said substantially horizontally disposed end portions of said wire element terminating in downwardly inclined portions which are connected to the lower frame so as to prevent buckling of the front row of springs, the upper frame being open at its front and including inclined portions which are unconnected with the front row of springs, means for connecting the inclined portions of the upper frame to said wire element so as to prevent inward or outward tilting of the front corner springs, and a brace wire hav- 110

ing connection with said wire element intermediate its ends and also connected with the lower frame to reinforce the aforesaid downwardly inclined portions of said wire 5 element in their action of preventing buckling of the front row of springs.

3. A spring structure comprising upper and lower frames, rows of springs arranged between the frames, a wire extending across 10 the front row of springs and connected thereto and provided at its ends with rearwardly directed inclined portions which extend downwardly to the lower frame, means for connecting said downwardly inclined 15 portions of said wire to the lower frame so as to prevent buckling of the front row of springs, the upper frame being open at its front and including inclined portions which are unconnected with the front row 20 of springs, and means for connecting said inclined portions of the upper frame to said wire so as to prevent inward or outward tilting of the front corner springs.

4. A spring structure comprising upper 25 and lower frames, rows of springs arranged between the frames, a wire extending across the front of the structure between the upper and lower frames and having connection with all of the springs of the front row and 30 also having connection with the lower frame adjacent the rear of the latter so as to prevent inward or outward buckling of the

front row of springs intermediate their ends, the upper frame having connection with said wire at spaced points so as to prevent outward or inward tilting of the front corner 35 springs.

5. A spring structure comprising upper and lower frames, rows of springs arranged 40 between the frames, a wire extending across the front of the structure between the upper and lower frames and having connection with all of the springs of the front row and also having connection with the lower frame adjacent the rear of the latter so as to prevent inward or outward buckling of the front row of springs intermediate their ends, 45 said wire having a plurality of kinks therein, the upper frame being open at its front and including inclined portions which engage said wire at the kinked portions of the latter, and means for securing said inclined portions of the upper frame to the kinked portions of said wire so as to prevent inward or outward tilting of the front corner 50 springs.

In testimony whereof we affix our signatures in presence of two witnesses.
